(57) **CLAIM**

The ornamental design for a pocket protector, as shown and described.

DESCRIPTION

FIG. 1 is a top front side perspective view of a pocket protector showing my new design;

FIG. 2 is a front view of the pocket protector;

FIG. 3 is a rear view of the pocket protector;

FIG. 4 is a right side view of the pocket protector, a left side view being a mirror image thereof;

FIG. 5 is a top view of the pocket protector; and,

FIG. 6 is a bottom view of the pocket protector.

The broken lines in the figures represent stitching that does not form part of the claimed design.
